UNITED STATES PATENT OFFICE.

CANAAN DE CAZEN, OF MONTREAL, QUEBEC, CANADA.

GUN.

1,317,434.

Specification of Letters Patent. Patented Sept. 30, 1919.

Application filed January 16, 1919. Serial No. 271,522.

To all whom it may concern:

Be it known that I, CANAAN DE CAZEN, residing at 121 Cherrier street, in the city of Montreal, in the Province of Quebec, in the Dominion of Canada, have invented certain new and useful Improvements in Guns; and I do hereby declare that the following is a full, clear, and exact description of the same.

10 The present invention consists essentially of different purpose barrels secured on the same stock, adapted to be used simultaneously or otherwise, said barrels being superposed in relation to one another and re-
15 movable from said stock.

The principal object of the invention is to devise a gun having two barrels, one being used as a rifle and the other as a shot gun, thus eliminating the inconvenience of carrying two guns and reducing the additional weight.

20 A further object of the invention is to provide a repeater gun having a simple lock mechanism and whereby the barrels, which are one above the other, may be, when desired, interchanged in their positions.

Another object of the invention is to provide a gun of this character whereby accurate shooting may be obtained by an improved sight arrangement for usage with these double purpose barrels.

30 Another object is to devise a gun having two different purpose barrels cheap of construction and particularly efficient and accurate.

The invention will be better understood with the aid of the accompanying drawings in which:

Figure 1 is a side elevation of the improved gun.

Fig. 2 is a vertical longitudinal sectional view of the lock case and a portion of the stock and barrels.

Fig. 3 is a horizontal longitudinal sectional view of the lock case and a portion of the stock and barrels.

Fig. 4 is a cross section on line A—A of Fig. 2.

Fig. 5 is a cross section through the barrels showing the adjustable front sight.

Fig. 6 is a cross section on line B—B of Fig. 2.

Fig. 7 is an enlarged front elevation of the rear sight.

55 In the drawings 1 is the stock which is

preferably bored horizontally at 2, and 3 is an enlarged hole communicating with the hole 2 and 4 is a downwardly projecting slot or cavity communicating with the horizontal enlarged hole 3. Adjacent said slot 4, the stock is enlarged to form a rectangular lock casing 5 which is provided with the open end 6 to form a barrel socket, and 7 and 8 are longitudinal openings on the top and bottom respectively for the ejection of the cartridges. 9 is a longitudinal opening on one side of said lock casing adapted to register with a magazine 10, and 11 are the slots in the bottom of the casing through which the trigger projects.

In the upper portion of said stock is provided a cell or housing 12, and 13 are suitable guide-ways provided on the upper and lower sides.

The barrels 14 and 15 are preferably integral and connected together by the web 16, and at their inner ends they have respectively the enlarged rectangular bores 17 and 18 adapted to receive the breech blocks 19 and 20. Said enlarged rectangular bores are provided with openings 21 and 22, adapted to register with the openings 7 and 8, and side openings 21^a and 22^a corresponding to opening 9. The barrel 14 is here illustrated as being adapted for shot while the barrel 15, which is of smaller diameter and preferably rifled, is adapted for bullets.

The breech blocks 19 and 20 are movable in the enlarged bores 17 and 18 and are respectively provided with longitudinal central holes 23 and 24 therethrough, and 25 and 26 are spring chambers communicating with said holes. Within said holes 23 and 24, are provided the firing pins 27 and 28 terminating in the firing points 29 and 30.

On said pins 27 and 28 are secured the tension spiral springs 31 and 32 which are located in the spring chambers 25 and 26 respectively. The rear ends of said firing pins 27 and 28 terminate with the rigid latch members 33 and 34.

The breech block 19 is for the shot barrel while the block 20 is for the rifle and 35 is a bar slidably mounted on said block 19 and 105 bent inwardly at its rear end to form a hook 36, and 37 is a pin or screw adapted to engage a slot 38 thereby limiting the movement of said bar. The breech block 20, being here illustrated as adapted for a 110

rifle barrel, is also provided with a bar 39 slidably mounted thereon, bent at its rear end inwardly so as to form a hook 40, and 5 41 is a pin or screw adapted to engage the slot 42 to limit the movement of the said bar. Each of said bars 35 and 39 is provided with a notch or depression to press the same forward.

A horizontal plunger rod 43 is provided 10 in the hole or spring chamber 3 in the lock casing 5, and 44 is a cross head bent to avoid the firing pins 27 and 28 and 45 is a spiral spring adapted to hold said rod normally in its forward position. At right angles to said plunger rod 43 is provided, preferably integral therewith, a lever 46 which is adapted to normally engage said vertical slot 4. The said lever when operated is turned out of engagement with the slot 4 20 and pulled rearwardly into the slot 3 thereby carrying the rod 43 and the head 44 rearward. The breech block 19 that is engaged (as shown in the drawings) with said head 44 by the hook or the bar 35 will be carried 25 out of the chamber or casing 17. When the lever 46 is released, the tension spring 45 will carry it back into its normal position, and at the same time carry the block 19 into its former position, and the tension of the 30 spring will cause the lever 46 to fall back and lock into the slot 4.

The breech blocks 19 and 20 are respectively provided with spring hooks 47 and 48 which are adapted to engage or grip the 35 rim of the cartridges, which are not illustrated in the drawings.

It will readily be seen that when one of the breech blocks is pulled out of its casing after firing a cartridge, that the said cartridge will be carried out of the cartridge 40 chamber into the breech block casing for ejection through the openings 21 and 7 or 22 and 8.

A spring catch or hook 49 is provided in 45 the casing 5 and is adapted to grip the fixed latch 33 on the firing-pin 27 for firing purposes, said spring catch 49 being secured to the bracket 50, and 51 is a link 50 pivotally secured to said catch at its upper end, and at its lower end is secured a crank member 52 which is also pivoted and is operated by the trigger 53. A similar spring 55 catch 54 is provided in the casing 5 opposite to said catch 49 and is adapted to grip the fixed latch 34 on the firing pin 28; said spring catch being secured to the bracket 55, and 56 is a link pivotally connected to said catch at one end and at its other end is secured a pivoted crank member which is 60 operated by the trigger 57.

58 is a fixed sight mounted on the clamp 59 which is secured on the rifle barrel by the screw 60 which projects through a hole in the web 16. A number of holes 61 are 65 provided to adjust the sight if necessary.

62 is a rotary sight which is preferably journaled in the slot provided in the housing 12. The sight consists of a cylindrical member 62 provided around its periphery with a plurality of lateral dents 63 and a 70 central V-shaped groove 64, eccentric in relation to the periphery of the cylindrical member 62, and it is so devised that by turning said cylindrical member, the sight will be lifted or lowered according to the distance, thus obtaining accurate shooting. A leaf spring 65 is applied below said cylindrical member 62, in the said slotted housing 12 and made to contact with the periphery of said cylindrical member 62 to cause friction and provide for proper adjustment of the sight.

The sight may also be adjusted sidewise by moving it on the shaft on which it is journaled.

The upper barrel, whether it is the shot or rifle, as already explained, may be, when desired, of the repeater type by the adaptation of a magazine 10 which is partly illustrated in Fig. 6 of the drawings.

What I claim as my invention is:

1. A gun of the character described comprising a stock, a lock case, transposable barrels secured to said lock case and individual breech blocks in said barrels substantially as described.

2. A gun of the character described comprising a stock and a lock case integral therewith, different purpose barrels secured to said lock case, and a breech block having a suitable firing pin, movably mounted in the inner end of each of said barrels substantially as described.

3. A gun of the character described comprising a stock, a lock casing attached to said stock, different purpose barrels secured to said casing, having each at one end thereof a breech block casing integral therewith, a breech block in each of said breech block casings having suitable firing pins operating in said blocks and provided at their rear ends with rigid latch members, substantially as described.

4. A gun of the character described comprising a stock and an integral lock casing, integral different purpose barrels transposedly secured at one end to said lock casing, each of said barrels having a breech block casing at one end thereof, a breech block slidably mounted in each of said casings, a spring held firing pin mounted in each of said breech blocks having at their rear ends rigid latch members, a plunger rod having a cross head at its forward end adapted to engage said breech blocks and a lever for operating said plunger rod substantially as described.

5. A gun of the character described comprising a stock and integral lock casing, said lock casing having a plurality of car-

tridge openings, integral different purpose barrels reversibly secured at one end of said lock casing each of said barrels having a breech block casing at one end thereof, said block casings having a plurality of cartridge openings registering with the openings in the lock casing, said breech blocks having catches for engagement with the cartridges at one end and hook bars at their other end, 10 spring held firing pins slidably mounted in said breech blocks having at their rear ends rigid latch members, a horizontal spring held plunger having a cross head at its forward end adapted to engage said breech blocks and a lever for operating said plunger rod, spring catches secured to individual triggers and adapted to engage said rigid

latches on said firing pins substantially as described.

6. A gun of the character described comprising a stock and a lock casing integral therewith, said lock casing having an ejecting slot and a magazine slot, a lock mechanism in said lock casing, a magazine discharging into said magazine slot, and integral rifle and shot barrels transposably secured to said lock casing substantially as described. 20 25

Signed at Montreal, Canada this 9th day of January 1919.

CANAAN DE CAZEN.
